United States Patent Office

Des. 230,337
Patented Feb. 12, 1974

230,337

BEVERAGE GLASS OR SIMILAR ARTICLE

Walter B. Achenbach, Toledo, Ohio, assignor to Owens-Illinois, Inc., Toledo, Ohio

Filed July 23, 1971, Ser. No. 165,876

Term of patent 14 years

Int. Cl. D7—01

U.S. Cl. D7—8

FIG. 1

FIG. 2

FIG. 4

FIG. 1 is a front perspective view of a beverage glass or similar article showing my new design;

FIG. 2 is a side perspective view from the left of FIG. 1;

FIG. 3 is a rear perspective view thereof; and

FIG. 4 is a side perspective view from the right of FIG. 1.

I claim:

The ornamental design for a beverage glass or similar article, as shown.
